Patented Jan. 29, 1957

179,607

PORTRABLE ELECTRIC HOUSEHOLD POWER UNIT

Alfred W. Madl, Milwaukee, Wis., assignor to John Oster
Manufacturing Co., Milwaukee, Wis., a corporation
of Wisconsin

Application April 19, 1956, Serial No. 41,135

Term of patent 14 years

(Cl. D89—1)

Fig. 1.

Des. 179,607

PAGE 2

Fig. 2.

Fig. 3.

Figure 1 is a perspective view of a portable electric household power unit embodying my new design, viewing the same from the top, front and one side thereof;

Figure 2 is a front perspective view thereof;

Figure 3 is a side perspective view thereof;

Figure 4 is a top plan view thereof, and

Figure 5 is a rear perspective view thereof.

The dominant features of my design reside in those portions thereof shown in full lines.

I claim:

The ornamental design for a portable electric household power unit, as shown and described.
